UNITED STATES PATENT OFFICE.

FRANCIS H. BUZZACOTT, OF CHICAGO, ILLINOIS.

DESIGN FOR A RANGE FIRE-CHAMBER PLATE.

SPECIFICATION forming part of Design No. 34,417, dated April 23, 1901.

Application filed March 21, 1901. Serial No. 52,242. Term of patent 7 years.

To all whom it may concern:

Be it known that I, FRANCIS H. BUZZACOTT, a citizen of the United States, residing at Chicago, in the county of Cook and State of Illinois, have invented and produced a new and original Design for a Range Fire-Chamber Plate, of which the following is a specification, reference being had to the accompanying drawings, forming a part hereof.

10 Figure 1 is a top or upper edge view of a range fire-chamber plate of my new and original design; Fig. 2, a view in front elevation of the same; Fig. 3, a view in vertical edge elevation, and Fig. 4 a section taken as indicated at line 4 of Fig. 2.

15 As shown in the drawings, the leading or material feature of my design consists in a plate A, having a substantially flat rear surface, vertical ribs a on the front surface of said plate, horizontal ribs a' , intersecting said vertical ribs, and a lower flange a^2 , parallel to and of somewhat greater width than the

ribs a' . The plate is designed to constitute the rear wall of the fire-chamber of a range, the width of the plate being equal to the width 25 of the range and the height of the plate being equal to the distance from the base of the range to the upper flue extending from the fire-chamber to the rear end of the range immediately beneath and parallel to the range- 30 top.

Having described my invention, what I claim as new, and desire to secure by Letters Patent, is—

The design for a range fire-chamber plate, 35 as herein shown and described.

In testimony whereof I have signed my name to this specification in the presence of two subscribing witnesses.

FRANCIS H. BUZZACOTT.
